US00D674709S

(12) **United States Design Patent**
Akana et al.

(10) **Patent No.:** US D674,709 S
(45) **Date of Patent:** ** Jan. 22, 2013

(54) **PACKAGING**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/426,064**

(22) Filed: **Jun. 29, 2012**

Related U.S. Application Data

(63) Continuation of application No. 29/363,816, filed on Jun. 15, 2010, now Pat. No. Des. 662,835, which is a continuation-in-part of application No. 29/354,604, filed on Jan. 26, 2010, now abandoned.
(51) **LOC (9) Cl.** **09-03**
(52) **U.S. Cl.** **D9/737; D9/432**
(58) **Field of Classification Search** **D9/430-433, D9/414, 418, 420-423, 529, 560; 206/278, 206/297, 299, 433, 457, 770, 737, 769, 776, 206/777, 778, 320; 229/100, 101, 103.3, 229/106, 107, 108, 108.1, 109, 110, 112, 229/116, 116.5, 117, 117.01, 117.03-117.08, 229/121, 122, 122.24, 122.29, 125.015, 126,**

229/152, 181.1, 185.1, 186, 201, 917, 922, 229/923, 930-933, 935, 937, 939, 942; 220/796

(57) **CLAIM**

The ornamental design for packaging, as shown and described.

DESCRIPTION

FIG. 1 is a front perspective view of packaging showing our new design;
FIG. 2 is a bottom perspective view thereof;
FIG. 3 is a front view thereof;
FIG. 4 is a rear view thereof;
FIG. 5 is a side view thereof;
FIG. 6 is another side view thereof;
FIG. 7 is a bottom view thereof; and,
FIG. 8 is a top plan view thereof.
